UNITED STATES PATENT OFFICE.

JAMES B. WRIGHT, OF NEW YORK, N. Y., ASSIGNOR TO WILLCOX AND GIBBS SEWING MACHINE COMPANY, OF NEW YORK, N. Y., A CORPORATION OF NEW YORK

GUIDE FOR OVEREDGE SEWING-MACHINES.

No. 874,816.

Specification of Letters Patent.

Patented Dec. 24, 1907.

Application filed May 9, 1906. Serial No. 315,849.

To all whom it may concern:

Be it known that I, JAMES B. WRIGHT, a citizen of the United States of America, residing in the borough of Brooklyn, in the city of New York, county of Kings, and State of New York, have invented a new and Improved Guide for Overedge Sewing-Machines, of which the following is a full, clear, and exact specification.

10 The object of my invention is to provide an overedging sewing machine with an improved construction of edge guide, which will facilitate the overedging of carpets or like fabrics, having projecting thread ends or 15 "whiskers" to be covered up by the over-seam stitches.

In the accompanying drawings I have shown my invention as applied to the Willcox and Gibbs overseam sewing machine known 20 as the "overlock" and forms of which are shown in Patents 472,094 and 472,095.

Figure 1 is a plan view of sufficient of the machine to show the application of my invention thereto; Fig. 2 is a side elevation; 25 Fig. 3 is a perspective view of the presser foot, with edge guide; and Fig. 4 is a perspective view of the needle hole plate with part of edge guide attached.

The cloth plate 5 of the machine carries a 30 needle hole plate 6, which is slotted at 7 for the feed dog and at 8 for the passage of the looper 9, as usual. The needle arm 10 and needle 11 and presser foot arm 12 may also be of usual construction.

35 The presser foot arm 12 carries at its front end a presser foot 13, which is provided on its right hand side with a deep pendent flange 14 inclined to the direction of the feed of the goods. A correspondingly inclined slot 15 is formed in the needle hole plate, as shown in Fig. 4, to receive this flange 14, which forms the edge guide for the goods to be overseamed. This flange does not extend quite to the chaining finger 17 which is carried 40 by the presser foot because the carrying forward of the flange 14 to the chaining finger would necessitate the cutting of the slot 15 through to the slot 8, and so weaken the

needle hole plate too much. I, therefore, secure to the surface of the plate 6, by a screw 50 18, or otherwise, a piece 19, which has an edge 20, to lie adjacent to that part of the presser foot which forms the base of the chaining finger and immediately beyond the edge guide 14 (Fig. 3). This edge 20 thus 55 confines the thread ends of the fabric in their backwardly projecting position into which they have been bent by the edge 14, as the fabric is fed through the machine, and keeps them bent back until the overseam stitches 60 have been formed around them to cover and bind them in place. The upper side of the presser foot may be provided with a cord guide 21 to be also covered in by the overseam stitches. I prefer also to provide on 65 the side of the upright guard plate 22, usually employed on the overlock machine, a horizontal guard plate 23 at a suitable distance above the cloth plate to prevent the overedged carpet or other fabric from curling 70 upwards as it passes out from under the presser foot.

I claim as my invention

1. The combination of the needle and looper of an overseaming machine with a 75 presser foot having an inclined edge guide, a needle hole plate slotted for the passage of the looper and inclined edge guide, together with a second edge guide immediately beyond the inclined edge guide and attached to 80 the needle hole plate, substantially as described.

2. The combination of the needle and looper of an overseaming machine with a 85 presser foot having an edge guide, an upright guard plate behind the presser foot and a horizontal guard carried by the upright plate above the cloth plate, as and for the purpose described.

In testimony whereof I have signed my 90 name to this specification, in the presence of two subscribing witnesses.

JAMES B. WRIGHT.
